WINDOW HOLDER

Filed July 29, 1929

Inventor:
Charles J. Christopherson,
By Rummel & Rummel,
Atty.

UNITED STATES PATENT OFFICE

CHARLES J. CHRISTOPHERSON, OF OAK PARK, ILLINOIS

WINDOW HOLDER

Application filed July 29, 1929. Serial No. 381,783.

The main objects of this invention are to provide improved means for retaining a vertically shiftable window in adjusted position without the aid of sash weights heretofore commonly employed; to provide an improved window holder which may be attached to the outside of the window frame so as to obviate the use of encasements heretofore employed for the sash weights; and to provide window holding means which may be mounted between the upper and lower window sashes to serve as a guide, which will present the outward appearance of the ordinary stop strips and which may be conveniently installed as a unit in existing structures.

An illustrative embodiment of this invention is shown in the accompanying drawings wherein:

Figure 1 is a vertical section of a window embodying the improved window holding device.

Fig. 2 is a horizontal section taken on the line 2—2 of Fig. 1.

Fig. 3 is a vertical section taken on the line 25 3—3 of Fig. 2.

Fig. 4 is a side elevation of the window holding device.

Fig. 5 is a section taken on the line 5—5 of Fig. 4.

30 In the form shown, the improved window holding apparatus comprises an endless belt movably mounted on the sides of the window frame and arranged to connect the frame with a vertically shiftable window sash, and means 35 for frictionally gripping the belt.

In the construction illustrated, the window frame 1 comprises vertical side members 2 and horizontal end members 3 which are mounted in a window opening in a wall 4.

40 Mounted on the inner and outer edges of the side members 2 are molding strips 5 and 6 which extend the full length of the window frame and abut against molding strips 7 and 8 on the top member of the frame. On the external face of each side member 2 and midway between the molding strips 5 and 6, there is an elongated housing 9 secured to the side members by screws 10 and serving as the 50 usual middle stop strip separating the

grooves 11 and 12 in which the lower and upper windows slide.

A pair of window sashes 13 and 14 are slidably mounted in the guideways 11 and 12 respectively. Formed in the lateral edges of the sashes 13 and 14 respectively are recesses 15 and 16 which receive the opposite edges of the housing 9, thereby retaining the sashes in their usual spaced relation.

The housings 9 are preferably made of 60 channel bars to provide an elongated hollow space for the window holding members which retain the window sashes in any position to which they may be slid.

In the form shown the holding members 65 comprise endless belts 17 and 18 which are carried on upper and lower pairs of pulleys 19 and 20 respectively, located within the housings. The belt 17 passes through a pair of slots 21 in the wall of the housing adjacent 70 the upper sash and has a lug 23 secured to it and seated in a recess in the sash so that the belt travels over the pulleys as the window sash is raised or lowered.

The belt 18 is carried by pulleys 20 and 75 passes outside of its housing through slots 22 and is connected to the lower sash by a lug 24.

Each of the belts is provided with a brake in the form of a resilient spring, 25 or 26 respectively, which is mounted on the housing 80 and bears on the inner part of the respective belt, to produce sufficient friction to sustain the weight of the sash. Preferably each side of each sash is provided with such window holding device.

85 The pressure of the spring in any installation is designed to create just enough friction between the inner flight of the belt and the wall of the housing to offset the pull of gravity on the sash.

The improved window holding device obviates the use of sash weights and the wall compartments necessary to house and conceal them and thereby admits of a greater window width in cramped places and also provides 95 a substitute that can be readily installed in old structures where spring bolt fasteners have been used.

100 Although but one specific embodiment of this invention has been herein shown and de-

scribed, it will be understood that details of the construction shown may be altered or omitted without departing from the spirit of this invention as defined by the following claim.

5 I claim:

In a device of the class described, a window frame, upper and lower window sashes each having recesses in their lateral edges slidably mounted in said frame, a guide member mounted on the side of said frame comprising a channel for retaining said sashes in spaced relation, a pair of belts movably mounted in said channel, each extending outwardly on 10 opposite sides thereof, means on each belt connected with one of said sashes, a pair of resilient members on said channel frictionally engaging said belts for holding said sashes in adjusted position.

15 20 Signed at Chicago this 25th day of June 1929.

CHARLES J. CHRISTOPHERSON.
